[57] ABSTRACT

Crochet galloon machines are improved for the purpose of making thereon double-sided looped cloth which does not have portions devoid of loops. This is achieved by providing the rear and/or the front loop holders at the locations of the weft yarn pressure sinkers with slots, recesses or milled portions. The sinkers are vertically shifted and guided in these recesses.

**DEVICE FOR PRODUCING DOUBLE-SIDED
LOOPED CLOTH UPON CROCHET GALLOON
MACHINES**

This invention relates to a device for producing double-sided looped cloth having no loop-free portions upon crochet galloon machines. These machines were used initially only to produce trimmings and braids.

Methods and devices for making double-sided looped cloth are known in prior art.

Close double-sided looped cloth is also made on crochet galloon machines which are then provided with special loop holders. However, this cloth has open channel-like spaces devoid of loops. The reason for this is that during the operation of the machine pressure sinkers must press the weft threads under the needles. Loop holders which are used to make loops upon the front and rear sides of the cloth could not be used as locations in which the pressure sinkers operate and since there are no long holders on these locations no loops are formed with the result that the finished cloth has open loop-free strips or passages. (German DDR Pat. No. 39,461).

An object of the present invention is, therefore, to provide a device which while retaining the general features of prior art procedures and without affecting the output of the machine, will make possible the manufacture of double-sided looped cloth having no loop-free portions.

Another object of the invention consists in the provision of a device of this type wherein the crochet threads of the base from which the loops project, are not movable any more relatively to each other in the direction of the weft.

These objectives are attained by providing the rear and/or front loop holders with longitudinal recesses, such as slots, milled portions or the like at the location of the weft yarn pressure sinkers, the pressure sinkers being so mounted in these recesses that they can be shifted vertically without interfering with the formation of the loops. These slots and milled portions provide at the same time a good guide for the pressure sinkers. Thus according to the present invention the loop holders are not eliminated any more in the location of the pressure sinkers but extend through the entire width of the machine.

According to a further embodiment of the invention each crochet needle is provided with a weft yarn guide and a pressure sinker as well as a front and rear loop holder.

This makes it possible to apply a weft thread to each warp thread and make the warp threads firm against shifting in the direction of the weft.

The invention will appear more clearly from the following detailed description when taken in connection with the accompanying drawings showing two embodiments of the inventive idea.

In the drawings:

FIG. 1 is a vertical section through a device of the present invention which uses combined pressure sinkers for the weft and the rear threads the needles being shown as located in their retracted end position.

FIG. 2 is a vertical section through a device of the present invention having separately driven pressure sinkers for the weft, the needles being also located in their retracted end position.

FIG. 3 is a stitch loop diagram.

FIG. 4 is a section along the line IV — IV of FIG. 3.

FIG. 5 is a perspective view of the device of the present invention.

FIG. 1 shows a crochet galloon machine of the present invention used for making double-sided looped cloth and having the usual operating needles, namely, hooked needles 1 and slide needles 2. The hooked needles 1 are fixed to a common rod 3, while needles 2 are fixed to a rod 4. A cam 6 actuating the rod 3 is used to reciprocate the needles 1, while a cam 5 actuating the rod 4 is used to reciprocate the needles 2. Loop holders 7 and 8 which are immovable, are used for forming the double-sided looped cloth. The rear plush loops are formed by pile warp threads 9, while the front plush loops are formed by pile warp threads 10. The basic fabric consists essentially of warp lengths shown enlarged in the loop diagram of FIG. 3 and indicated by the numeral 11. They are formed from warp threads 13 (FIG. 1). The basic fabric also includes weft loops 12 interconnecting the warps 11 (FIG. 3). To form the warp lengths 11 the needles receive the warp threads 13 from the laying rod 14 when the needles are in their front positions. The weft threads 12 are supplied by thread guides 15. As already stated, the weft threads 12 are used to join the lengths 11 in a manner known in prior art. The loop diagram of FIG. 3 shows several such weft threads 12 extend over only comparatively short stretches of the width of the fabric. A separate thread guide 15 is provided for each weft thread 12. To simplify illustration, only one thread guide is shown in the drawing. The eye printed needles 16 of the rod 14 carry out essentially a rotary movement around the operating needles. For that purpose the needles 16 move up and down and also move in the longitudinal direction of the machine. The up and down movement of the needles 16 is carried out by the cam 17. In order to provide movement of the needles 16 in the direction of the longitudinal axis of the machine, the rod 14 is slidably mounted upon a guide 18. This arrangement of the rod 14 is well known in the art and for that reason is not shown in detail. The thread guides 13 for the weft threads 12 carry out a movement only in the longitudinal direction of the machine. This is also well known and, therefore, not illustrated. For that purpose the rod 19a of the thread guides is caused to reciprocate in its longitudinal direction. The pile warp threads 10 used for the formation of the front plush side, are guided by separate thread guides 19 which are fixed to a rod 20. The rod 20 is raised and lowered by a cam disc 21. For that purpose a rod 22 is provided with a claw 23 engaged into longitudinal grooves 24 of the rod 20. The pile warp threads 10 are laid alternately under two operating needles. The rod 20 must be moved in its longitudinal direction to the extent of two operating needles when it is shifted longitudinally in the claw 23. This drive is also well known and therefore, not illustrated. The pile warp threads 9 for the rear plush loops are guided by separate thread guides 25. These thread guides 25, as distinguished from the thread guides 19, carry out a movement only in the longitudinal direction of the machine and again to the extent of two operating needles. The thread guides 25 are carried by a rod 26. The longitudinal movement of the thread guides 13, 19 and 25 takes place above the operating needles. As is known, it is necessary to avoid the formation of loops by the pile warp threads 9 and 10 and the weft threads

12. For this reason they must be brought after the laying under the operating needles. For this reason, as already stated, the thread guides 19 of the pile warp threads 10 are movable up and down, but not the thread guides 15 and 25. Pressure sinkers 27 are, therefore, provided for the weft threads 12 and the pile warp threads 9, the pressure sinkers being movable only up and down by a cam disc 28. The front notches 29 of the pressure sinker 27 engage the weft threads 12 and move them after laying under the needles 1. The notches 30 of the pressure sinkers 27 carry out the same operation in relation to the pile warp threads 9.

The general purpose is to provide a closed pile cover upon the front side as well as the rear side of the basic fabric. Pressure sinkers 27 are necessary since the thread guides 15 of the basic wefts 12 carry out a movement only along the machine. The pressure sinkers move the weft threads 12 under the operational needles. If an uninterrupted plush cover is to be produced, it is necessary to provide a loop holder 7 and/or 8 between every two operational needles. Then there is not more room for the pressure sinkers 27 since this space is occupied by the loop holders. It was, therefore, necessary to leave out the loop holders 7 and/or 8 at those locations wherein the pressure sinkers 27 were present. The result was that the finished fabric had longitudinal strips with no plush loops.

This drawback is eliminated by the present invention. According to the present invention the loop holders 7 are provided with slots (FIG. 1) or grooves (FIG. 2) in which the pressure sinkers 27 are guided.

If the pressure sinkers 27 are located in the front side of the machine, namely, between the loop holders 8 and the thread guides 19, then the construction of FIG. 2 is used wherein the pressure sinkers 27 are guided in the grooves of the loop holders 8.

If the thread guides 25 for the pile warp threads 9 are made movable up and down in the same manner as the thread guides 19, then it is not necessary to provide the pressure sinkers 27 with the notches 30.

FIG. 3 shows the stitch loop diagram of the finished fabric from the rear side. The plush loops are shown therefore, as being formed by the pile warp threads 9. The front side of the finished fabric appears precisely the same as the rear side, whereby the plush loops are then formed by the pile warp threads 9.

Thus an important feature of the present invention is that loop holders as well as pressure sinkers are pro-

vided without interruptions along the entire width of the machine, so that the finished fabric will not have strips or passages without loops.

Furthermore, the present invention provides a basic fabric wherein the warp lengths 11 cannot be shifted transversely to the longitudinal axis of the finished fabric upon their weft threads 12. For that purpose, as shown in FIG. 3, the weft threads 12 are shifted relatively to each other, so that for all practical purposes the reversing part of a weft thread 12 lies at each warp length 11. For this reason a pressure sinker 27 must be provided between every two operating needles along the entire width of the machine. Furthermore, a loop holder 7 and/or 8 must be always provided between two operating needles without interfering with the pressure sinkers 27. This is accomplished in accordance with the present invention by providing the loop holders with passages or grooves in which the pressure sinkers 27 are so mounted that they can be raised and lowered.

FIG. 3 illustrates the warp threads 13 and the weft threads 12. The guiding of the threads for the front loops 9 is shown in FIG. 4.

As illustrated in FIGS. 4 and 5 the formation of loops 9 and 10 takes place by loop holders 7 and 8. FIG. 5 shows that the pressure sinkers 27 move through grooves or cut out portions of the loop holders 7 and out of them during up and down movements. The threads are not shown in FIG. 5 so as not to complicate the illustration.

We claim:

1. In a crochet galloon machine, a device for making looped cloth the base of which consists of warp lengths interconnected by weft threads, said device comprising operating needles, loop holders located between all of said needles over the entire width of the machine and having longitudinally extending recesses, and sinkers guided in said recesses and operable for pressing the weft threads below the operating needles.

2. A device in accordance with claim 1, wherein said recesses consist of slots, said sinkers being freely movable through said loop holders in said slots.

3. A device in accordance with claim 1, wherein said recesses consist of grooves, said sinkers being guided through said loop holders in said grooves.

4. A device in accordance with claim 1, wherein said sinkers have notches for their weft threads and additional notches for their looped threads.
